B. Singer, Atty.

UNITED STATES PATENT OFFICE.

ROBERT WAUGH, OF LONDON, ENGLAND.

FASTENING FOR HAND BAGS.

Application filed December 5, 1924, Serial No. 754,115, and in Great Britain August 13, 1924.

This invention relates to fastenings for hand bags and the like and has for its object to provide such devices which are simple in construction and yet which give great security in use and prevent the accidental opening of the bag or the like.

In general a fastening constructed according to the invention comprises a member carried by one part of the bag or frame which 10 member is adapted to engage another member on the other part or frame when in the closed position, the first mentioned member being connected to the carrying handle, or the like in such a manner that when the bag 15 or the like is carried by the handle or the like the member is maintained in the engaged position by the weight of the bag which acts in the contrary direction to that in which it is necessary to move the member 20 to disengage it.

Two such fastening members are preferably employed on a hand bag or the like one end of the usual form of handle being connected to each and in this manner the bag 25 is additionally secured. Each engaging member connected to the handle is preferably spring controlled the spring tending to keep it in the engaged position and this member is preferably formed as a lever one 30 end of which forms the actual engaging part whilst the other end constituted a handle for effecting the disengagement against the action of the spring and the handle of the bag is preferably connected to this end.

35 And in order that the invention may be better understood it will now be described with reference to the accompanying drawings in which:—

Fig. 1 is an elevation of a hand bag with 40 the invention applied thereto.

Fig. 2 is an elevation of one of the fastening devices detached and to a larger scale, shewing the engaged position.

Fig. 3 is a similar view to Fig. 2 but in 45 the disengaged position.

Fig. 4 is a top plan of Fig. 2.

Fig. 5 is an under plan of part of Fig. 3.

Fig. 6 is an end elevation of part of Fig. 2.

Fig. 7 is a section through the frame of 50 the hand bag shewn in Fig. 1 with the fastener in the engaged position.

Fig. 8 is a similar view to Fig. 7 in the disengaged position but approaching the engaged position.

55 In the drawings 9 is the hand bag suit-

ably attached at the top to a hinged frame comprising a front 10 and back 11 having a top or flange 12. On the flange 12 of the back 11 two pivoted catches are disposed a desired distance apart as shewn. Each catch 60 comprises a base plate 13 riveted to the flange 12 and formed with upstanding lugs 14 which carry a pivot pin 15 between them and projecting on each side. To the projecting ends a lever 17 is pivoted by down-bent portions 16. One end of the lever is formed as a handle 18 and the other end is bent round to form the actual catch 19. A spring 20 is disposed around the pivot 15 between the lugs 14 and one end 21 comes 70 on the plate 13 whilst the other end 22 comes beneath the handle 18 the spring tending to keep the catch 19 in the engaged position. 23 is a ring of metal attached to the lever 17 between the pivot 15 and handle 18. 24 is a 75 strap or the like forming the handle for the hand bag. The ends of this strap are fixed to the rings 23 as shewn in Fig. 1. 25 are apertures in the flange 12 through which the catches 19 pass.

The member 10 of the frame has riveted thereto plates 26 bent at right angles as shewn so that they come beneath the catches 19, which engage in apertures 27 therein; the free ends of these plates are slightly 85 curved at 28 as shewn (Figs. 7 and 8) to press against the bevelled ends 29 of the catches 19 to force up the catches when closing the bag.

When the bag is in the closed position 90 in order to open it the handles 18 are pressed down against the action of the springs. This raises the catches 19 from the apertures 26 and allows the parts 10 and 11 of the frame to be separated. To close the bag 95 these parts are brought together when the engaging curved edges 28 and bevelled ends 29 force up the catches 19 as previously explained, the catches then springing into the apertures 26. When carrying the bag by 100 the handle 24 it will be appreciated that the weight of the bag acts upon each lever 17 in such a manner that its catch 19 is maintained in position by the weight thus preventing accidental opening.

In some cases only one fastening device need be used the handle being suitably connected thereto. Other forms of fastening device could also be made according to the invention, which is not to be regarded as 110

limited to that particularly described, provided the fastening device is so connected to the handle or the like and the bag that when carried by the handle the weight is 5 adapted to maintain the fastening in the closed position. Further the invention can be applied to any desired suitable form of bag, purse or other suitable receptacle of a similar nature.

10 What I claim and desire to secure by Letters Patent in the United States of America is:—

15 1. A hand bag fastener comprising a pair of frame members hinged together and having overlapping portions each provided with an opening, said openings being in registry when said members are in closed position, a fastening member pivotally mounted at a point intermediate its ends on one of said frame members, the said fastening member having one end arranged to engage in said openings and provided at the opposite end with a manipulating handle, a coiled wire spring on the pivot of the fastening member having one end engaging the fastening member and the other end the frame to keep the fastening member pressed towards the 20 engaging position, and a suspending element connected to the fastening member intermediate the pivot and the handle also to keep the fastening member pressed towards

the engaging position by the weight of the bag when suspended from said element.

2. A hand bag fastener comprising a pair of frame members hinged together and having overlapping portions each provided with an opening, said openings being in registry when said members are in closed position, a base plate attached to one of the said frame members and formed with upstanding lugs, 35 a pivot pin carried by said lugs and projecting on each side thereof, a fastening member having downbent portions at a point intermediate its ends and pivoted on the projecting ends of the said pivot pin, the said fastening member having one end arranged to engage in said openings and provided at the opposite end with a manipulating handle, a coiled wire spring on the pivot of the fastening member and located between 40 the said lugs, having one end engaging the fastening member and the other end the frame to keep the fastening member pressed towards the engaging position, and a suspending element connected to the fastening member intermediate the pivot and the handle 45 also to keep the fastening member pressed towards the engaging position by the weight of the bag when suspended from the said element.

In witness whereof I affix my signature.
ROBERT WAUGH.
